UNITED STATES PATENT OFFICE

EDWARD J. HOFFMAN, OF BOSTON, MASSACHUSETTS, ASSIGNOR TO ELDEEN AUTOMATIC HOSIERY MENDER INC., OF BOSTON, MASSACHUSETTS

REKNITTING NEEDLE

Application filed November 20, 1928. Serial No. 320,575.

This invention relates to needles adapted for use in repairing ravel or runs in knitted articles and pertains more particularly to hand operated needles of the type having a hooked end and a latch or bridge, pivoted to swing toward and from the hook, thereby to retain a thread of the material being repaired within the hook during certain stages of the reknitting operation. The present invention is in the nature of an improvement upon the needle described and claimed in my pending application Serial No. 266,718, filed April 2, 1928, and the principal object of the invention is to provide a magnetized element such as a magnetized bar or electromagnet so disposed with respect to the needle that the magnetic field surrounding one of its ends exerts its attraction upon the pivoted latch or bridge and tends continuously to draw the latch away from the hook.

Although the magnetized bar or other magnet may be employed with any usual type of reknitting needle having a hooked end and pivoted latch, it has especial utility when utilized in association with the needle shown and described in my said application. Accordingly the recommended embodiment of the present invention which is illustrated in the accompanying drawings comprises the former needle and a preferred type of magnetized bar connected thereto in operative relationship.

In said drawings, Fig. 1 is a side view of the improved needle, showing the latch in normal position; and Figs. 2 to 5 show somewhat diagrammatic representations of successive steps or stages in the repairing operation accomplished by the improved needle.

As more fully described in my said application, my prior device preferably comprises a body or handle portion 7 formed of any suitable material such as fused metal, a steel needle 8 fixed at one end within the handle and having a curved hook 9 at its outer end, a latch or bridge 10 loosely pivoted to the needle in proximity to the hook 9 so that it may swing forwardly to close the hook or backwardly to lie substantially alongside the needle, and a resilient clasp member 11 having its outer end bent transversely of the

needle to provide an abutment 12 which serves as a thread stop member. The magnetized steel bar 13 is preferably connected to the handle 7 so as to extend parallel to the needle 8, and preferably has its forward end bent transversely toward the latch 10, as indicated at 14. The tip of said forward end 14 is spaced from the arc described by the swinging end of the latch so that the latch does not contact with the magnetized end of bar during its swinging movement; but the end 14 is sufficiently close to the latch to attract the tip of the latch and hold it substantially at right angles to the needle in the normal position shown in Fig. 1.

The bar 13 may be rigidly attached to the handle 7 in any suitable manner, for example by means of opposed plates 15 clamped upon the handle and the bar by bolt 16 and nut 17. Obviously, however, other means may be employed rigidly to connect the bar in proper position with respect to the needle and latch. The bar 13 accordingly furnishes a substantial store of magnetism which will exert its magnetic force, especially in the field surrounding the end 14, for a considerable period of time. It will be found, therefore, that the latch 10 is supported in its normal position with respect to the needle (Fig. 1) except when urged either rearwardly toward the shank of the needle, or forwardly toward the hook 9, by contact with such external objects as the threads of the article being repaired, during the reknitting operation.

The four representative stages of this operation which are illustrated in Figs. 2 to 5 are not intended to portray precise positions of the needle, but are shown for the purpose of indicating particularly the automatic operation of the magnetically controlled latch 10. In Fig. 2 the hooked end of the needle has been inserted downwardly through the last existing loop 18 at the end of a run in the material, and this loop thread has carried the latch rearwardly toward the shank of the needle. In Fig. 3 said loop thread has slipped beyond the end of the latch, after further downward progress of the needle, and the latch has reassumed its normal posi-

tion; the loop 18 being now temporarily retained between the clasp member 11 and the needle shank 8, and the hook 9 having reached beyond the next thread 19 of the ravel.

- 5 In Fig. 4 the needle is being withdrawn to carry the thread 19 through the loop 18, and the latch 10 has been closed upon hook 9 by contact with loop 18, which is slipping over the latch and the hook guarded thereby.
- 10 And in Fig. 5, the thread 19 has been drawn upwardly through loop 18 to form a new loop 19^a, the latch 10 being released and restored to normal position by attraction of the magnetized bar end 14.

15 With loop 19^a serving as the initial loop of a second series of steps, the operation is repeated successively until the ravel or run is completely repaired. It will be understood that these operations are performed at great speed and with little, if any, visual attention on the part of the operator. Accordingly, the provision of the magnetized bar 13, which ensures that the latch 10 is quickly restored to a position normal to the needle, either 20 from its forward or rearward position, upon its release, is of great assistance to sustained speed in operation without faulty operation of the needle itself.

30 The functions of the latch 10, clasp element 11 and stop member 12 are set forth with greater particularity in my said pending application; it being understood that the stop member, which serves as a contacting abutment against the threads of the 35 material to impede forward progress of the needle, may take various forms. It will also be understood that other forms of magnets, for example electromagnets, may be employed in place of the bar 13; and that other 40 details of construction may be varied without departing from the essence of this invention as defined in the appended claims.

A needle constructed in accordance with this invention permits the repairing operation to be performed at greater speed, without interruption due to defective functioning of the latch, than is possible with needles heretofore used; and accordingly appreciably decreases the time and labor consumed.

50 I claim:

1. A device of the class described comprising a needle having a hooked end, a latch adapted to close said hooked end, a magnet disposed in spaced relation to the latch and 55 adapted to attract the latch away from said hooked end, and means rigidly connecting the magnet with the needle.

2. A device of the class described comprising a needle having a hook at its forward 60 end, a latch pivoted to the needle in proximity to the hook whereby the needle may swing forwardly to close the hook and rearwardly toward the needle, a magnetized element disposed in spaced relation to the tip 65 of the swingable latch and adapted to attract

the latch away from the hook in one direction and away from the shank of the needle in the opposite direction, and means connecting the magnetized element with the needle.

3. A device of the class described comprising 70 a needle having a hook at the forward end, a latch pivoted to the needle in proximity to the hook, whereby the latch may swing forwardly to close the hook and rearwardly toward the shank of the needle, a magnetized bar extending substantially parallel to the needle and having one of its ends disposed in closely spaced relation to the tip 75 of the swingable latch, whereby the latch is normally attracted and held substantially at right angles to the needle by the magnetism of said bar end, and means connecting the bar to the needle.

4. A device of the class described comprising 80 a handle, a needle fixed longitudinally in the handle and having a hook at its free forward end, a latch pivoted to the needle in proximity to the hook, whereby the latch may swing forwardly to close the hook and rearwardly to lie substantially alongside the 85 needle, a magnetized bar extending substantially parallel to the needle in the plane of the swingable latch, said bar having its forward end in closely spaced relationship to the tip of the swingable latch when said 90 latch is substantially at right angles to the needle, so that the latch is attracted away from the hook in one direction and away from the needle in the opposite direction, and means rigidly connecting said bar to 95 the handle.

5. A device of the class described comprising 100 a handle, a needle fixed longitudinally in said handle and having a thread-engaging hook at its free forward end, a latch pivoted to the needle in proximity to the hook, whereby the latch may swing forwardly to close the hook and rearwardly toward the shank of the needle, a stop member connected 105 with the handle and disposed transversely of the needle to the rearward of the latch pivot whereby to constitute an abutment adapted to meet the fabric and thereby impede forward progress of the needle, a magnetized element disposed in spaced relation to the tip of the swingable latch and adapted to attract the latch away from the hook in one direction and away from the needle in the opposite direction, and means rigidly connecting the magnetized element to the handle.

6. A device of the class described comprising 110 a handle, a needle fixed longitudinally in the handle and having a thread-engaging hook at its free forward end, a latch pivoted to the needle in proximity to the hook, whereby the latch may swing forwardly to close the hook and retain a thread therein and rearwardly to lie substantially alongside the 115 needle, a stop member connected with the 120

handle and disposed transversely of the needle to the rearward of the latch pivot whereby to constitute an abutment adapted to meet a thread and thereby impede forward progress of the handle, and a magnetized element disposed in operative relationship to the latch for attracting the latch away from the hook.

7. A device of the class described comprising a needle having a hooked end, a latch pivoted to the needle and adapted to close said hooked end, a magnet spaced from the latch and adapted to attract the latch, and a stop member disposed transversely of the needle and constituting an abutment adapted to impede progress of the needle into the fabric.

15 8. A device of the class described comprising a needle having a hooked end, a latch pivoted to the needle and adapted to close said hooked end, a magnet spaced from the latch and adapted to attract the latch, and a stop member disposed transversely of the needle and constituting an abutment adapted to meet a thread of the fabric, thereby to impede progress of the needle into the fabric.

25 In testimony whereof I affix my signature.

EDWARD J. HOFFMAN.
